UNITED STATES PATENT OFFICE.

AARON M. BILLSTEIN, OF RIDERWOOD, MARYLAND, ASSIGNOR TO THE LORD BALTIMORE PRESS, OF BALTIMORE, MARYLAND, A CORPORATION OF DELAWARE.

BOX.

1,257,067.

Specification of Letters Patent. Patented Feb. 19, 1918.

Application filed March 10, 1915. Serial No. 13,386.

To all whom it may concern:

Be it known that I, AARON M. BILLSTEIN, a citizen of the United States of America, and resident of Riderwood, Baltimore county, Maryland, have invented certain new and useful Improvements in Boxes, of which the following is a specification.

The present invention relates to improvements in boxes and particularly to paper boxes adapted for the sale of candies or small articles which are sold in relatively inexpensive packages. The object of the invention is to provide a box of the character referred to which will be inexpensive 10 of construction and which is provided with means adapting it for use as a toy, it including parts by which a plurality of different pictures may be displayed by slight manipulation of a member.

20 In the accompanying drawings,

Figure 1 is a perspective view of a box constructed in accordance with the present invention;

Fig. 2 is a vertical sectional view;

25 Fig. 3 is a front elevation of the box showing the picture bearing member in a slightly different position from that represented in Figs. 1 and 2;

Fig. 4 is a vertical sectional view through 30 the box with the parts arranged as in Fig. 3;

Fig. 5 is a plan of the blank from which the box illustrated in Figs. 1 to 4 is formed;

35 Figs. 6 and 7 are elevations of part of the box showing the picture displaying member in other positions.

Referring to the drawings, it will be seen that the particular embodiment of the invention illustrated is a folding paper box formed from a single blank or sheet 1. The 40 section of the blank which when folded constitutes the front of the box is provided with an extension 2 which extends upwardly above the top of the body of the box and may be provided on its forward face with 45 suitable advertising matter.

The closure for the upper end of the box is provided with an extension 3 on one face of which are printed a plurality of sectional pictures, adapted to be successively displayed through slots 4 provided in the body 50 of the front wall of the box as shown. In the embodiment of the invention illustrated,

the closure extension 3 is provided with two sectional pictures, the sections of one alternating with those of the other and each section being of a height not exceeding the width or height of the bar like portions 5 of the box separating the apertures or slots 4. It will be seen that when the top closure of the box is in the position shown in 60 Figs. 1 and 2, in which the extension 3 thereof is projected into the body of the box, its maximum extent, one of the pictures will be displayed through the apertures or slots 4, and when said closure is given a slight 65 outward movement or the parts are positioned as shown in Figs. 3 and 4, the other picture on said extension 3 will be displayed, the previously exposed picture being concealed by the wall of the box. By imparting 70 slight longitudinal movement to the extension 3, the pictures can be alternately displayed, the general effect being that of "moving pictures." As the closure is further withdrawn, other changes such as represented in Figs. 6 and 7 may be obtained, the 75 construction shown providing for four different views.

The character of pictures, and the number of slots or apertures 4 may be varied within 80 wide range, and it will be seen that the invention provides a very simple box adapted to be also employed as a toy which enhances the selling value of the articles or commodities placed therein.

The apertures 4 are preferably not produced entirely at the time of cutting the blank, but the outlines thereof are delineated by heavy scoring 7, the portions within said score lines being subsequently removed either 90 by a dealer or purchaser.

The manner in which the box is formed from the blank shown in Fig. 5 will be readily understood.

Having thus described the invention, what 95 is claimed and desired to be secured by Letters Patent is:

A combined receptacle and toy comprising a box having a plurality of apertures formed in a side wall, and a closure for the 100 box having an extension which when the box is closed is positioned entirely therein to extend across and completely close said apertures, the outer face of said closure ex-

tension being provided with a plurality of sectional pictures, the sections of different pictures being so related that when the closure is moved to and from closed position the said pictures will be successively displayed through the apertures in the side wall of the box.

In testimony whereof I affix my signature in presence of two witnesses.

AARON M. BILLSTEIN.
